UNITED STATES PATENT OFFICE.

WILLIAM H. RICHMOND, OF MOUNT PLEASANT, ASSIGNOR TO THE ARBOR CITY CHAIR COMPANY, OF ANN ARBOR, MICHIGAN.

SWING.

SPECIFICATION forming part of Letters Patent No. 555,887, dated March 3, 1896.

Application filed August 13, 1895. Serial No. 559,186. (No model.)

To all whom it may concern:

Be it known that I, WILLIAM H. RICHMOND, a citizen of the United States, residing at Mount Pleasant, in the county of Isabella and 5 State of Michigan, have invented certain new and useful Improvements in Swings, of which the following is a specification, reference being had therein to the accompanying drawings.

10 My invention is especially designed to be used as a house or porch swing, which may be suspended from the ceiling and when not in use drawn up out of the way, so that the space occupied by it in swinging may be used 15 for other purposes.

The invention consists in the peculiar construction, arrangement, and combination of parts, all as more fully hereinafter described.

In the drawings, Figure 1 is a vertical longitudinal section showing it in full lines in its folded position and in dotted lines as in use. Fig. 2 is a similar section showing the swing as in use. Fig. 3 is a horizontal section on line $\alpha\alpha$, Fig. 1. Fig. 4 is a detached 25 perspective view of a portion of the platform. Fig. 5 is a detail view of the pivotal connection of the hanger-bars. Fig. 6 illustrates the construction of the folding seat.

A are hanger-bars hinged at their upper 30 ends to the ceiling or other support, preferably by means of the hooks B. These hooks have screw-threaded shanks a and right-angle bends b , upon which latter the hangers are pivoted, being held from disengagement therefrom by the cotter-pins c. The hooks B are secured in pairs to the strips C, which may be 35 screwed or otherwise secured to the ceiling.

D are rods or cross-bars connecting the lower ends of each pair of hanger-bars. E is 40 a platform pivotally supported upon said rods, preferably by providing the side bars, E', of the platform with notches F adapted to engage with the rods C and held from accidental disengagement therefrom by the hooks G engaging with the staples G'. At each end of 45 the platform E is secured a folding seat comprising the seat-section H, pivotally secured between the bars A a short distance above the platform, and the back-section I pivoted 50 at its lower end upon the rods D.

The pivotal connection between the seat H

and the bars A preferably consists of the pins d formed at each end of the front bar, e, of the seat, passing part way through the hanger-bars A and secured thereto by the screw f. 55 The back-section I consists of the outwardly-bowed side bars, g, across the upper part of which the back extends, and the cross-bar h, adapted to engage with notches i formed on the under side of the seat-section, all so arranged that the seat and back may be adjusted to different angles and when not in use may be folded up substantially into line with the bars A. 60

J is a shelf or table detachably pivoted to 65 the bars A by the short pins j at each corner engaging with corresponding apertures in the bars A.

The parts being thus constructed the swing may be used either with or without the shelf 70 J in position, which latter may be readily removed by springing the bars A enough to disengage the pins j therefrom. When in place the shelf J will always maintain its horizontal position whatever the inclination of the 75 swing, as it forms one side of a parallelogram frame. Thus the swing may be used not only for amusement, but many kinds of work for which a table is required may be performed in the swing while it is in motion. 80

When the swing is not in use the seats may be folded by disengaging the bar h from the notches i and then turning the seat and back sections up into line with hanger-bars, the bowed or bent form of the back-section allowing it to close up more compactly than if it were straight. The swing may now be drawn up to the ceiling by means of a cord or rope K passing over a pulley L. As it is drawn up the parallelogram-frame will flatten out, 90 so that when finally secure in its raised position it occupies the least possible space. The lower seat is prevented from falling down by a suitable fastening device, such as the hook M, which secures the end of the back-section 95 to the bars A.

What I claim as my invention is—

1. A folding swing comprising a parallelogram frame consisting of the hanger-bars A hinged to the ceiling or other support, and the 100 platform E pivotally secured to the lower end of said hangers upon cross-rods F, in combi-

nation with folding seats upon opposite sides of said frame, each consisting of the seat-section H pivotally secured between the hanger-bars and an outwardly-bowed back-section I 5 pivoted to the rod F, and provided with a cross-bar h adapted to engage with notches i on the seat-section, said sections H and I being adapted to fold up approximately into line with the hanger-bars, and means for drawing 10 up the lower end of the swing, substantially as described.

2. In a swing, the combination with a parallelogram frame consisting of the hanger-bars A hinged at their upper ends to the ceiling or 15 other support, and the platform E pivotally secured at the lower end of said bars, of a seat secured to side of said frame and a shelf or table pivotally secured to said frame above the seat adapted to maintain its horizontal position during the movement of the swing, substantially as described.

3. In a swing, the combination with a parallelogram frame consisting of the hanger-bars A hinged at their upper ends to the ceiling or 20 other support, and the platform E pivotally secured to lower ends of said bars, of a seat

secured at the side of said frame and shelf or table J provided with the corner pivots j, engaging with corresponding apertures in the sides of the hanger-bars and adapted to be 30 disengaged therefrom by springing the bars, substantially as described.

4. In a swing the combination with a parallelogram frame consisting of the hanger-bars A hinged at their upper ends to the ceiling or 35 other support, and the platform E pivotally secured to the lower ends of said bars, of a shelf or table pivotally secured to said hanger-bars above the platform, adapted to maintain its horizontal position during the movement 40 of the frame, and folding seats upon opposite sides of said frame, each comprising the seat-section H and back-section I pivotally connected to the hanger-bars and adjustably engaging with each other, substantially as described.

In testimony whereof I affix my signature in presence of two witnesses.

WILLIAM H. RICHMOND.
